UNITED STATES PATENT OFFICE.

JOHN H. ANDERSON, OF ST. PAUL, MINNESOTA.

CUFF CONSTRUCTION.

Application filed May 20, 1927. Serial No. 192,827.

My invention relates to an improved shirt cuff and a stiffening or bracing means therefore, the latter being more aptly designated as a stay for keeping the cuff in proper taut condition to improve its appearance and utility.

In the accompanying drawings—

Fig. 1 is a fragmentary view of the end of a sleeve and my improved cuff and stay 10 attached thereto, the latter being shown in section.

Fig. 2 is a horizontal sectional view about as on line 2—2 in Fig. 1.

Fig. 3 is a side elevation of my improved 15 cuff of the type fixed to a shirt sleeve and a modified form of stay shown inwardly of a broken out portion of the cuff.

Fig. 4 is a horizontal sectional view of the connected ends of the cuff in Fig. 3 about as 20 on line 4—4 in said Fig. 3.

Fig. 5 is a side elevation of a preferred form of the cuff stay.

Fig. 6 is a plan view of my improved cuff 25 with stays and laid out flat and preparatory to being put on a sleeve, and Fig. 7 is the sleeve end to which a cuff as in Fig. 6 is to be attached.

Fig. 8 is a plan view of my improved cuff without the stays and Fig. 9 is the sleeve 30 end to which the cuff as in Fig. 8 is adapted to be attached.

Referring to the drawings by reference numerals my improved cuff is particularly of the kind known as soft-cuffs comprising a 35 quadrangle piece of fabric doubled over to provide a wide exterior flap 10^A and a narrower inner flap 10^B. Said inner flap is provided near its edge with a number of buttonholes 10^H and likewise the shirt sleeve 40 end band 11 is provided with corresponding buttonholes 11^H, and 12 are a suitable number of cloth straps or links each with two buttons 13 and 14 said straps being buttoned transversely to connect the shirt sleeve band 11 and the said inner flap 10^B, in a manner to hold the adjacent edges close to each other 45 and entirely covered up when the cuff is bent over to connect its free ends by suitable cuff buttons of the link type, snap type or other type desired. In Fig. 3 the cuff is an integral part of the shirt sleeve 11^S.

The main object in providing the links 12 is to have a flexible connection between the shirt sleeve and the cuff to permit the latter 50 to be retained in attractive and taut condi-

tion by the additional stay means presently to be described and regardless of whether the buttonholes for the buttons of said links 12 are in proper alinement, it being understood that the shirt sleeve and its cuffs may shrink 60 more or less after washing and any variation in shrinkage will be immaterial in regard to the cuff as the links 12 will merely connect said parts and may be at various angles but always invisible when in use because they 65 are covered by the flap 10^A.

I will now describe the stay devices I employ in connection with the above described cuff and which may also be used with the type of cuff formed integral with the sleeve 70 as in Fig. 3.

15 represents any suitable type of cuff link with a shank member 15^S connecting its heads, and 16 are the cuff link holes in the cuff. The simplest form of stay is shown in 75 Figs. 1 and 2 and comprises a flat shoe-shaped piece of suitable material such as sheet celluloid designated 17. 17^H is a head part on said stay 17 with a horizontal slit 17^S in which is slidably engaged the shank 80 18^S of a small cuff button 18 of the usual type. This button 18 is normally vertically above the cuff link 15 and its shank 15^S as shown. 17^N is the neck of head 17^H and is simply a 85 reduced upper part of stay 17 from which part the stay projects downwardly to form a heel 17^H engaging the lower folded part of the cuff adjacent its open end, 17^T comprising a horizontal extension or toe of the stay 90 extending along the inner bottom of the cuff. 90

19 is a vertical opening in the upright part of the stay to allow for free vertical movement of the stay, and the link shank 15^S passes through said opening. 20 is a rubber band engaging the rear part of the neck 17^N 95 thence passed upwardly over the shank 18^S of button 18 at both sides of the stay, thence both parts extended downwardly to and under the shank 15^S of the cuff link and thence upwardly and forwardly to engage the notch 100 formed by the front neck part 17^N, the entire band thus being in tension. It is obvious that the upwardly directed parts of the band pull upwardly on link 15 which is freely movable in the slot 19 and the same 105 tension pulls downwardly on the head part of the stay and causing the lower heel and toe portion to press down within the crease of the cuff. The entire body of the stay tends to stiffen the open end parts of the 110

cuff and the above tension means create a taut condition of the cuff between the cuff link and the lower edge of the cuff.

Figs. 3, 4 and 5 show variable construction 5 of the stay members presently to be described, and Fig. 6 includes stays of the one piece type just described.

The stay illustrated in Fig. 3 is particularly for attached type cuffs, its head part 10 17^H being comparatively large and below said head formed with an interiorly directed and widening gap formed with a central downward extension or secondary gap 17^G normally straddling the link shank 15^S. 15 21 are vertically spaced pins fixed in the upright part of stay 17 and engaged by the slotted parts 22^S of a stay-slide 22 which is thus oscillatably retained against the stay 17 and has an inwardly and downwardly 20 directed notch 22^N and above said notch another upwardly opening notch 22^{N'} normally frictionally engaging and straddling the shank 15^S of the link 15. The notched part is impelled upwardly by a rubber band 25 20^X engaging in the terminus of the lower notch 22^N and extending upwardly over the top of head 17^H and engaging in a notch 23 in the top part and being under tension tends to pull slide 22 upwardly so its 30 notched part 22^{N'} pushes up on shank 15^S. Simultaneously the tension in the band between notches 22^N and 23 pulls down on head 17^H and the entire stay is pressed down against the creased part of the cuff.

35 The modified form of stay in Fig. 5 shows the slide 22 of angular shape with an inwardly directed ledge 22^L to engage the link shank 15^S and the rubber band engages the lower end of the slide and is movable in a vertical slot 24 in the heel part of the stay 40 17, the upper end of the band engaging the notch 23 of the stay. The tension in the rubber pushes ledge 21^L into frictional contact with the link, upwardly and simultaneously pushes the stay 17 downwardly.

45 The use of my improved cuffs and stay means therefor has been fully disclosed in the above specification. It is obvious that a cuff with a narrow inner flap covered completely by the outer flap reveals none of the connecting links nor the stays described. The stiffening means and the manner of connecting the cuff to the shirt sleeve band as described provides for a neat appearing cuff 50 at all times regardless of the condition of the sleeve end, providing of course that the latter is connected to the cuff as described.

It will be noted that in the use of my device the straps 12 are removed from their 60 operative positions when shirts and cuffs are to be washed and there are thus no buttons to be torn loose in laundering machines or wringers. The straps 12 are previously mentioned automatically adjustable to any variations in the registering positions

of the buttonholes due to variation in construction and shrinkage of sleeve bands and cuffs.

In Fig. 1 that part of the rubber band 20 extending outwardly from button 18 of the 70 wrist band is designated 20^F and it will be understood that this part being always under tension draws the shank of said button outwardly and thereby keeps that part of the sleeve away from the nearest 75 link 12 and in taut condition and neat appearance, said shank 18^S of the button being freely movable in the slot 17^S.

I claim:

1. A detachable cuff comprising a quadrangular piece of soft material adapted to be folded to provide a narrow inner flap and a wide upper flap and means for detachably securing the edge part of said inner flap to the wrist band of a shirt, said cuff flaps provided with registering button holes for a cuff link to hold the open ends of the cuff in closed position, said means for securing the cuff to the wrist band of a shirt, consisting of a number of straps each with two buttons secured to it and adjacent its ends, said inner flap edge adapted to be placed in close parallel relation to the edge of a wrist band of a shirt, said wrist band and said edge portion of the cuff provided each with a row of buttonholes registering approximately in pairs, each said strap arranged to be buttoned with one end to the cuff and the other end to sleeve. 80 85 90 95

2. A soft cuff comprising a quadrangular piece of soft material and folded to form adjoining inner and outer elongated flaps said inner flap narrower than the outer flap, means for connecting the said folded cuff ends comprising registering buttonholes 100 for a cuff link, a shank button for connecting the ends of the wrist band, and means for bracing and tautening the cuff at its folded end portions and extending toward the center part of the cuff, said cuff bracing and tautening device comprises for each 105 end of the cuff a stay of flat pliable material arranged to lie between the folds of the cuff, and a vertical aperture provided in said stay and through which the cuff link is 110 passed and a tension element on each stay engaging its top part above the cuff link shank extending from the outer part of the upper head portion thence inwardly and over the shank of the wrist band button, thence downwardly under the shank of the cuff link, thence upwardly to the inner and upper part of the stay, to press the stay downwardly, the lower part of the stay forming an elongated base engaging 115 in the folded part of the cuff. 120 125

3. A folded shirt cuff comprising an inner narrow flap and an integral wider and outer flap, said folded cuff adapted to be brought together with its free ends and means com- 130

prising a cuff link with its shank passed through said end parts of the cuff, cuff stiffening means detachably insertible between said flaps of the cuffs at their open 5 ends and comprising a flat-shoe-shaped element with an upright part adapted to be arranged close to the said cuff link shank, a base adapted to engage and brace the lower folded parts of the cuff and inwardly from 10 the open ends thereof, and a horizontal head part on said stay, a slide member on said

vertical part comprising an L-shaped pliable piece slidably mounted vertically on the main stay member, tension means engaging said head and the under side of said slide 15 member to impel it upwardly and press its horizontal arm upwardly to frictionally engage the shank of the cuff link and simultaneously press the stay member down for the purpose set forth. 20

In testimony whereof I affix my signature.
JOHN H. ANDERSON.
